[57] CLAIM

The ornamental design for a combined frame extrusion and spline for framing awnings, as shown and described.

DESCRIPTION

FIG. 1 is a perspective view of a combined frame extrusion and spline for framing awnings showing my new design, in unassembled position;

FIG. 2 is a perspective view thereof in assembled position, the broken line showing of the secured awning fabric is for illustrative purposes only and forms no part of the claimed design;

FIG. 3 is an end elevational view of the extrusion, the opposite end being a mirror image thereof;

FIG. 4 is a top plan view thereof;

FIG. 5 is a side elevational view, the opposite side being a mirror image thereof;

FIG. 6 is an end elevational view of the spline, the opposite end being a mirror image thereof;

FIG. 7 is a side elevational view, the opposite side being a mirror image thereof;

FIG. 8 is a bottom plan view thereof; and

FIG. 9 is a top plan view thereof.

FIG. 3

FIG. 4

FIG. 5

FIG. 6

FIG. 7

FIG. 8

FIG. 9
